UNITED STATES PATENT OFFICE.

BENJAMIN R. SINGLETON AND CHARLES D. HOFFMAN, OF ST. LOUIS,
MISSOURI.

CABLE-GRIP FOR RAILROADS.

SPECIFICATION forming part of Letters Patent No. 391,202, dated October 16, 1888.

Application filed February 2, 1888. Serial No. 262,796. (No model.)

To all whom it may concern:

Be it known that we, BENJAMIN R. SINGLETON and CHARLES D. HOFFMAN, citizens of the United States, residing at St. Louis, in the 5 State of Missouri, have invented a new and useful Improvement in Cable-Grips for Railroads, of which the following is a specification, reference being had to the accompanying drawings.

This invention relates to certain improvements in cable-railway grips, which will be hereinafter more particularly described, and pointed out in the claims.

In the accompanying drawings, forming part 15 of this specification, Figure 1 is a side view of the grip and showing the frame, grip-bar, pawl, and ratchet. Fig. 2 is a front view of the grip. Fig. 3 is a transverse vertical section through the grip, and also shows the frame 20 suspended from its seat under the car-body. Fig. 4 is a side view of the wedge removed from the shoe. Fig. 5 is a longitudinal vertical section of the shoe, showing the rollers inside of it. Fig. 6 is a side view of the grip-carriage, showing the grip and frame suspended from the car-body. Fig. 7 is a plan view of 25 the top of the grip-carriage. Fig. 8 is a transverse vertical section of a double shoe on line $x x$ of Fig. 9, to be used on cable-ways which 30 have switch terminals. Fig. 9 is a top view of Fig. 8. Fig. 10 shows in perspective the grip-frame seated in its position under the car-body. Fig. 11 is a perspective view of a device for fastening the frame in the seat. Fig. 35 12 is a vertical section on $y y$ of Fig. 11.

A is a cast-metal shoe or case formed as shown in the drawings. The lower side is straight lengthwise and flat crosswise. The upper part is formed like the frustum of a cone, having 40 on one side a long slit, a' , and on top at the small end a slot, d' . This shoe A is held in the frame-work B by straps C C', which are firmly secured to it, and are connected to the frame B, which frame is made of wrought-iron 45 and attached and secured to the frame-work of the car.

D is a wedge of chilled cast-iron having its lower side straight lengthwise, but convex transversely very slightly. The upper part is 50 made to conform to the corresponding interior of the shoe A, and on its small end there is a

projecting lug, d, which fits into the slot d' of the shoe A. On the large end of D there is a hole, d'' , to which is secured the end of the operating-lever G by a screw-bolt, g'' . The 55 shoe A is supplied with a series of concave rollers, R' R' R', which move freely in the case or shoe A.

G is a lever having the fulcrum at g in the frame B. The long lever G' extends up into 60 the car, and on it there is a pawl, R, controlled by a spring, r, and working over a segment-ratchet, r', which is attached to the beam B'.

The lower part of the lever G' is bent at right angles at g' and g'' . The short lever G is 65 pivoted to the wedge D at g'' by a screw-bolt. When the lever G' is moved in the direction of the arrow, the wedge D is partly withdrawn from the shoe and the large end is also slightly raised at the same time, while the lug d slides 70 up the slot d' and correspondingly lifts that end also free from the cable at the same time that the large end is lifted.

Fig. 8 represents two of the grips arranged on the frame back to back, to be used on cable 75 roads having switch terminals, for the purpose of working the cars reversely.

The grip, as above described, can be hung in the wrought-iron frame B, (shown in the drawings, but more distinctly in the perspective Fig. 10 and Fig. 6,) and is suspended from the middle of a car-floor, or at the front platform, as may be most convenient, or from a separate grip-carriage, which is to be put at the forward end of a car and can be run into 80 the platform when the track ends with a switch and cars have to be changed off from one track to the other. When, however, the track has a loop at the terminals, then the grip can be either at the end or middle of the car, 85 and no separate grip-car is required. When the grip is in the middle of a car, the grip bar or lever G' is operated from the front platform by a lever and connecting-rod running under the floor of the car and attached to the 90 grip-lever G, so that the driver will have complete control of the grip and the brakes at the same time. The grip is applied to the present 95 style of cars, thus effecting a saving of expense for cars and saving in the expense of a heavy 100 grip-car, as now used on cable roads. Figs. 11 and 12 represent the method of securing

the frame B in its seat *a*. The bolt *c* is loose and can be turned in the slot *c''*; and a round rod, *c'*, is run through the loop of the bolt *c* on top of the plate *p*, and thus the frame B is held 5 firmly in its seat *a*.

We claim—

1. In a cable-grip, the conical-formed hollow shoe A, having in its lower part a series of rollers and on its smaller end a slot, *d'*, in 10 combination with a wedge-shaped shoe having a lug corresponding in shape to the slot, substantially as described.

2. The combination of the hollow shoe A, the frame B, the wedge D, having a lug, *d*, to 15 correspond with a slot, *d'*, in the end of the

shoe, and the lever G, substantially as described.

3. The fastening device consisting of the bolt *c*, having one end curved, the block *p*, and bolt *c'*, in combination with the frame B 20 and the seat *a*, substantially as described.

In testimony that we claim the foregoing as our own we hereto affix our signatures in presence of two witnesses.

BENJAMIN R. SINGLETON.
CHAS. D. HOFFMAN.
